HOSE DRIER.

APPLICATION FILED JULY 23, 1903.

NO MODEL.

2 SHEETS—SHEET 2.

UNITED STATES PATENT OFFICE.

CHARLES MICHAEL BOWMAN, OF LEBANON, PENNSYLVANIA.

HOSE-DRIER.

SPECIFICATION forming part of Letters Patent No. 758,168, dated April 26, 1904.

Application filed July 23, 1903. Serial No. 166,693. (No model.)

To all whom it may concern:

Be it known that I, CHARLES MICHAEL BOWMAN, a citizen of the United States, residing at Lebanon, in the county of Lebanon and State 5 of Pennsylvania, have invented certain new and useful Improvements in Hose-Driers; and I do declare the following to be a full, clear, and exact description of the invention, such as will enable others skilled in the art to which 10 it appertains to make and use the same.

This invention relates to hose-driers of that type in which wet hose are supported in an inclosed space while being subjected to the action of a drying medium.

15 One object of my invention is to provide a simple and compact device of this character which will occupy but little space and yet have sufficient capacity to accommodate a great number of hose-sections.

20 Other objects are to provide means for folding, wringing, and cleaning the hose before it is placed upon the drying rack or stand and to hasten the drying action by imparting motion to said rack or stand.

25 A further object is to provide a device which will be simple in construction, durable in use, very efficient for the purpose intended, and comparatively inexpensive of production.

With these and other objects in view the 30 invention consists of certain novel features of construction, combination, and arrangement of parts, as will be more fully described, and particularly pointed out in the appended claims.

In the accompanying drawings, Figure 1 is a 35 vertical sectional view through my improved hose-drier. Fig. 2 is a horizontal sectional view through the same. Fig. 3 is a detail view showing the folding and wringing rolls in side elevation. Fig. 4 is a detail view of a modified 40 form of hose-supporting shelf or frame.

Referring to the drawings by numeral, 1 denotes a hose-supporting rack or stand, which comprises a rotatable shaft 2, mounted vertically in a suitable frame 3 and provided 45 at regular intervals with hose-supporting shelves or frames 4. The vertical shaft or upright 2 may be mounted in any desired manner. As illustrated in the drawings, it is journaled in suitable bearings formed in a base-plate 5 and a top plate 6 of the frame 3,

said upper and lower plates 5 and 6 being connected by vertical standards 7. The hose-supporting shelves or frames 4, of which any desired number may be used, comprise hubs or sleeves 8 and radially-disposed arms 9, which project from said hubs and upon which the hose rest. The frames 4 may be mounted to revolve upon the shaft 2, in which case the hubs are supported by fixed collars or flanges 10 upon the shaft, as shown, or they may be fixed to 60 said shaft, in which case the hubs are secured to the shaft. The sections or lengths of hose are wound spirally upon the arms 9, as shown in Fig. 2, and in order to space the coils the arms are provided with vertical sockets or recesses 65 11, which may be formed, as shown in Figs. 1 to 3, by bending said arms, as shown, or by providing vertical pins or projections, as seen in Fig. 4. The hose is folded or pressed flat, as hereinafter described, before it is placed upon 70 frames 4, so that it will be supported edge-wise, as shown.

Any suitable gearing may be provided for rotating the shaft 2. As illustrated, I provide a horizontal drive-shaft 12, which is mounted 75 in suitable bearing and provided at its inner end with a beveled gear 13, which meshes with a similar gear 14, secured to said vertical shaft 2. The outer end of the shaft 12 is provided with a pulley 15, which may be connected by 80 a belt to any suitable source of power in order to operate the apparatus.

In order to rapidly dry the hose, I inclose the rack or stand 1 in a removable casing or covering 16 and discharge hot air or other 85 drying medium into the casing below said rack. The inclosing casing is preferably made of canvas or other suitable flexible material or fabric, so that it may be easily thrown back to expose the rack when the sections of hose 90 are being placed upon or removed from the same. A pipe 17, leading from a hot or cold air drum or blower 18, enters the lower portion of the casing and extends to a point below the center of the rack 1, where its upturned open 95 end discharges the drying medium, which circulates about the hose within the casing and quickly dries the same. While this drying action is going on the rack is preferably revolved in order to hasten the drying. The shaft 19, 100

upon which the fan in the blower-casing 18 is mounted, is preferably driven from the shaft 12 by connecting-pulleys 20 upon said shafts by a belt 21, as seen in Fig. 2, although, if so desired, the blower may be operated in any other manner and may be of any well-known or preferred construction.

- In order to wring and fold or compress the hose to adapt it to be placed upon the rack and
- 10 in order to clean the same, I first pass the same between a pair of rollers 23 and then between a pair of rotary brushes 24. Said rollers and brushes are secured upon shafts journaled in bearings formed in uprights 25 upon a base 26.
  - 15 The shafts of the rollers are geared to rotate together, as are also the shafts of the brushes, by providing gears 27 upon each of the upper shafts, which mesh with similar gears 28 upon the lower shafts, as shown in Fig. 3. The shaft
  - 20 of the upper roller and the shaft of the upper brush are connected to rotate together by passing a belt 29 about pulleys 30, secured to said shafts, and the shaft of the upper brush is adapted to be driven from shaft 12 by passing
  - 25 a belt 31 about pulleys 32, secured upon said shafts, as shown in Fig. 2.

In the operation of my invention when the shaft 12 is rotated motion will be imparted to the rack 1, the fan or blower 18, the brushes 30 24, and the rollers 23 by means of the gearing previously described. The wet hose is first passed between the rollers and brushes to fold the same and remove as much water and dirt as possible and is then coiled upon one of the 35 shelves or frames 4 of the rack, as previously explained. The casing 16 is then drawn around the rack to inclose the same, so that the circulation of the drying medium discharged through pipe 17, together with the rotation of 40 the rack, will rapidly dry the hose upon the latter.

From the foregoing description, taken in connection with the accompanying drawings, the construction and operation of the invention 45 will be readily understood without requiring a more extended explanation.

Various changes in the form, proportion, and the minor details of construction may be resorted to without departing from the principle or sacrificing any of the advantages of 50 this invention.

Having thus fully described my invention, what I claim, and desire to secure by Letters Patent, is—

- 55 1. A hose-drier, comprising a suitable frame, a shaft or upright mounted in said frame, hose-supporting shelves or frames upon said shaft, said shelves or frames being provided with means for spacing the coils of the hose, an inclosing casing for said frame, and means for supplying a drying medium to said casing, substantially as described.
- 60 2. A hose-drier, comprising a suitable frame, a vertical shaft mounted to rotate in said frame, 65 hose-supporting shelves or frames upon said

shaft, means for spacing the coils of the hose upon said shelves, a removable inclosing casing for said frame, means for rotating said frame, and means for supplying a drying medium to said casing, substantially as described. 70

3. A hose-drier, comprising a suitable frame, a vertical shaft mounted to rotate in said frame, hose-supporting shelves or frames revolubly mounted upon said shaft, means for spacing the coils of the spirally-wound hose upon said shelves, a removable inclosing casing for said frame, a drive-shaft, means for imparting motion to said vertical shaft from said drive-shaft, a blower for forcing a drying medium into said casing, and means for operating said blower from said drive-shaft, substantially as described. 75

4. In a hose-drier, a drying-rack provided with means for supporting the line of hose in a folded or compressed condition with the folds 80 spaced apart, substantially as described.

5. In a hose-drier, the combination with a suitably-mounted shaft or upright, of hose-supporting shelves or frames having arms provided with means for spacing the coils of the spirally-wound hose, substantially as described. 90

6. In a hose-drier, the combination with a suitably-mounted shaft or upright of hose-supporting shelves or frames having radial 95 arms provided with recesses or sockets adapted to receive the coils of the hose and to space the same, substantially as described.

7. In a hose-drier, the combination with a suitably-mounted rotatable shaft, of hose-supporting shelves or frames revolubly mounted upon said shaft and having arms provided with recesses or sockets adapted to receive the coils of the hose and to space the same, substantially as described. 100

8. In a hose-drier, the combination with a suitably-mounted rotatable shaft, of hose-supporting shelves or frames, revolubly mounted upon said shaft and comprising hubs, and arms projecting radially from said hubs and 110 bent to form recesses or sockets adapted to receive the coils of the hose and to space the same, substantially as described.

9. In a hose-drier, a drying-rack provided with supports for a coiled hose, said supports 115 having means for spacing and supporting the coils of the hose in a folded or compressed condition, substantially as described.

10. In a hose-drier, a drying-rack provided with hose-supports having seats to receive the 120 coils of hose in a folded or compressed condition, substantially as described.

In testimony whereof I have hereunto set my hand in presence of two subscribing witnesses.

CHARLES MICHAEL BOWMAN.
